[57] CLAIM

The ornamental design for a weather vane, as shown and described.

DESCRIPTION

FIG. 1 is a perspective view of a weather vane showing my new design;

FIG. 2 is a top view thereof;

FIG. 3 is a bottom view thereof;

FIG. 4 is a front elevational view thereof;

FIG. 5 is a rear elevational view thereof; and,

FIG. 6 is a left side elevational view, with the right side being a mirror image thereof.

The broken line showing of indicia on the tail fin in FIGS. 1 and 6, and the broken line showing of potted plants in FIGS. 1 and 4, are for illustrative purposes only and forms no part of the claimed design.
